UNITED STATES PATENT OFFICE.

WILLIAM WELLES BOSWORTH, OF NEW YORK, N. Y.

DESIGN FOR A LAMP-POST.

40,826.

Specification for Design.

Patented Aug. 16, 1910.

Application filed June 14, 1910. Serial No. 566,866. Term of patent 14 years.

To all whom it may concern:

Be it known that I, WILLIAM WELLES BOSWORTH, a citizen of the United States, residing in the city of New York, borough of Manhattan, in the county and State of New York, have invented a new, original, and ornamental Design for a Lamp-Post, of which the following is a specification, reference being had to the accompanying drawing, forming a part thereof.

The figure is a side elevation of a lamp post showing my new design.

I claim:

The ornamental design for a lamp post, as shown.

WILLIAM WELLES BOSWORTH.
